VANITY TABLE

Earl R. Wright, 8124 Victoria Ave.,
South Gate, Calif. 90280

Filed Oct. 3, 1969, Ser. No. 19,406

Term of patent 14 years

Int. Cl. D6—01

U.S. Cl. D33—6

FIG. 1 is a front view of a vanity table showing my invention.

FIG. 2 is a side of FIG. 1.

FIG. 3 is a top view of FIG. 1.

FIG. 4 is a back view of FIG. 1.

FIG. 5 is a fragmentary front view of the upper portion of the vanity table showing side mirrors closed and an articulated slat-type closure drawn in front of the shelfed compartment below the mirrors.

FIG. 6 is a fragmentary sectional view taken in a transverse horizontal plane indicated by line VI-VI of FIG. 1.

FIG. 7 is sectional view taken in the transverse horizontal plane indicated by line VII-VII of FIG. 1.

I claim:

The ornamental design for a vanity table, as shown.
